UNITED STATES PATENT OFFICE.

RICHARD JONAS, OF BERLIN-CHARLOTTENBURG, GERMANY, ASSIGNOR TO THE FIRM OF
ARTHUR KOPPEL, A. G., OF BERLIN, GERMANY.

VESSEL FOR CONVEYING MATERIALS.

No. 895,025.

Specification of Letters Patent.

Patented Aug. 4, 1908.

Application filed February 7, 1908. Serial No. 414,849.

To all whom it may concern:

Be it known that I, RICHARD JONAS, mechanical engineer, a subject of the German Emperor, and a resident of Berlin-Charlottenburg, Germany, have invented certain new and useful Improvements in Vessels for Conveying Materials, of which the following is a specification.

My invention relates to improvements in vessels for conveying materials, such as riveted metal transporting-boxes and cars and the like. To enable such vessels to be readily seized and tipped or otherwise handled by the workmen the rim has been provided either with ordinary angle-irons, or with hand-rails whose web, attached to the edge of the vessel, is bulbed at the top. Such hand-rails, however, are found to be wanting in rigidity, so that the edge of the vessel is liable to get distorted in the course of time. I overcome this defect by the employment of angle-iron of the well-known bulbous type, which I apply to the vessel in such manner that the terminally bulbed web constitutes a ledge. The advantages of such bulb angle-iron over ordinary angle-iron are obvious. The ledge or flange presented can be much more readily grasped by the workman without there being any danger of his hands getting injured; and the angle-iron can be run completely round a transporting-vessel of the usual rectangular shape, right over the corners, without any particular caution having to be observed or special machinery or tools employed. With ordinary angle-iron the protruding web is extremely apt to get torn off. This is obviated by my invention, which insures superior strength and greater convenience in manipulation. In the event of the bulbed angle-iron getting bent over, the bulb yields sufficient material to prevent the web from being wrested off or fractured, even though strained and stretched to a certain extent. Thus bulb angle-iron combines the advantages of ordinary angle-iron in point of rigidity, with those of prior bulbous hand-

rails in respect to handy shape and capability of bending.

One form of construction of the invention is illustrated in the accompanying drawing, in which the figure is a fragmental cross-sectional view.

r is the top portion of the wall of the transporting-vessel, to which there is applied the web, *b*, of the angle-iron, whose outwardly projecting web, *a*, terminates in a bulb, *a*¹. The web, *b*, may be furnished on the inside with a shoulder, *b*¹, which butts against the rim of the wall, *r*. The angle-iron may be bolted, riveted, welded, or otherwise secured to the vessel.

To facilitate gripping the angle-iron may be of the round-backed type, with the bulbed web, *a*, downwardly curved as shown in the drawing. The angle-iron may naturally be of any suitable dimensions and of any desirable material.

Having thus described my invention, I declare that what I claim is:

1. A transporting-vessel, and an angle-iron secured by its one web to the outer edge thereof, while its other web projects outwardly and is terminally bulbed, substantially as and for the purpose described.

2. A transporting-vessel, and an angle-iron passing around all the walls of the same and secured by its one web to the outer edge thereof, while its other web projects outwardly and is terminally bulbed, substantially as and for the purpose described.

3. A transporting-vessel, and a round-backed angle-iron secured by its web to the outer edge thereof, while its other outwardly projecting web curves downwardly and is terminally bulbed, substantially as and for the purpose described.

Signed at Berlin this 24th day of January 1908.

RICHARD JONAS.
